United States Patent Office

Des. 186,745
Patented Nov. 24, 1959

186,745

ALARM BOX

Harold K. Nansel, Waverly, Nebr., assignor to Notifier Corporation, Lincoln, Nebr., a corporation of Nebraska

Application January 20, 1958, Serial No. 49,328

Term of patent 14 years

(Cl. D72—1)

Fig. 1.

Fig. 2.

Fig. 3.

Fig. 4.

Fig. 5.

Fig. 1 is a perspective view of an alarm box embodying my new design;

Fig. 2 is a rear elevational view of same;

Fig. 3 is a front elevational view of same;

Fig. 4 is a side elevational view of same; and

Fig. 5 is a top plan view of same.

The dominant features of my new design are shown in solid lines in the drawing.

I claim:

The ornamental design for an alarm box, as shown and described.
